UNITED STATES PATENT OFFICE.

ARTHUR LANGERFELD, OF NEW YORK, N. Y., ASSIGNOR TO JAMES A. MILLER AND ROBERT B. MILLER, OF CHICAGO, ILLINOIS.

DESIGN FOR A SHEET-METAL ELBOW.

SPECIFICATION forming part of Design No. 18,986, dated April 2, 1889.

Application filed January 25, 1889. Serial No. 297,576. Term of patent 14 years.

To all whom it may concern:

Be it known that I, ARTHUR LANGERFELD, a citizen of the United States, residing in the city, county, and State of New York, have invented certain new and useful Improvements in a Design for a Sheet-Metal Elbow, fully described and represented in the following specification and the accompanying drawings, forming a part of the same.

10 This design consists in an elbow provided with straight ends B and an intermediate curved portion, A, the straight ends having flutes or corrugations parallel to their axes, and the intermediate curved portion, A, having spiral flutes, ribs, or corrugations disposed as shown in the annexed drawings, in which—

Figure 1 is a perspective view of an elbow embodying my design, and Fig. 2 is a cross-section of the same on line α α in Fig. 1.

15 The spiral disposition of the flutes or ribs intermediate to the straight ends of the elbow

produces a novel and ornamental appearance, and the annexed drawings display the effect of such spiral disposition by a series of spiral lines, c, shown perspectively upon the curved 25 portion of the elbow A.

Having thus set forth my invention, the design I claim is—

The design for an elbow provided with straight ends B and an intermediate curved 30 portion, A, the straight ends having flutes or corrugations parallel to their axes, and the intermediate curved portion, A, having spiral corrugations, substantially as herein set forth.

In testimony whereof I have hereunto set my 35 hand in the presence of two subscribing witnesses.

ARTHUR LANGERFELD.

Witnesses:

A. O. KITTREDGE,
THOS. S. CRANE.
